Primary Examiner — Mark A Goodwin*Assistant Examiner* — Benjamin M Weeks(74) *Attorney, Agent, or Firm* — Walter M. Egbert, III; Gerard M. Donovan; Reed Smith LLP(57) **CLAIM**

The ornamental design for a binocular mount, as shown and described.

DESCRIPTION

FIG. 1 is a right side isometric view of a binocular mount showing our new design;

FIG. 2 is a left side isometric view thereof;

FIG. 3 is a front, bottom-left side isometric view thereof; FIG. 4 is a left side isometric view with the binocular mount pivoted upward;

FIG. 5 is a front, bottom-left side isometric view with the binocular mount pivoted upward;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof; and,

FIG. 11 is a bottom plan view.
